(57) **CLAIM**

We claim the ornamental design for a waste receptacle, as shown and described.

DESCRIPTION

FIG. 1 is a perspective view of a waste receptacle in accordance with a first embodiment of our new design; FIG. 2 is a front elevation view thereof; FIG. 3 is a left side elevation view thereof, the right side elevation view being a mirror image thereof; FIG. 4 is a rear elevation view thereof; FIG. 5 is a top plan view thereof; FIG. 6 is a bottom plan view thereof; FIG. 7 is a perspective view of a waste receptacle in accordance with a second embodiment of our new design; FIG. 8 is a front elevation view thereof; FIG. 9 is a left side elevation view thereof, the right side elevation view being a mirror image thereof; FIG. 10 is a rear elevation view thereof; FIG. 11 is a top plan view thereof; and, FIG. 12 is a bottom plan view thereof.
The broken lines depict unclaimed environmental subject matter and form no part of the claim.
